(57) **CLAIM**

The ornamental design for an ergonomic applicator, as shown and described.

DESCRIPTION

FIG. 1 is a front perspective view of an ergonomic applicator according to the invention;

FIG. 2 is a back perspective view of an ergonomic applicator according to the invention;

FIG. 3 is a side view of an ergonomic applicator showing my new design; and,

FIG. 4 is a side opposite that shown in FIG. 3.

The claim is limited to the shaded side surfaces only. The portions of the ergonomic applicator that are shown in broken lines form no part of the claimed design.
